United States Patent Office

Des. 187,183
Patented Feb. 9, 1960

187,183

TROPHY BASE

Ray E. Dodge and Ada W. Dodge, Miami Beach, Fla.,
assignors to Dodge, Inc., Chicago, Ill., a corporation of
Illinois

Application December 23, 1957, Serial No. 49,021

Term of patent 14 years

(Cl. D29—23)

Fig. 1

Fig. 2

Fig. 3

Fig. 4

Figure 1 is a front elevational view of a trophy base, showing our new design;

Fig. 2 is a side elevational view;

Fig. 3 is a top plan view; and

Fig. 4 is a front perspective view thereof.

The dominant feature of our design resides in the portion shown in full lines.

We claim:

The ornamental design for a trophy base, as shown and described.
